UNITED STATES PATENT OFFICE.

JAMES J. BURKE, OF HARTFORD, CONNECTICUT.

STEAM-ENGINE.

SPECIFICATION forming part of Letters Patent No. 722,083, dated March 3, 1903.

Application filed January 21, 1902. Serial No. 90,649. (No model.)

To all whom it may concern:

Be it known that I, JAMES J. BURKE, a citizen of the United States, residing at Hartford, in the county of Hartford and State of Connecticut, have invented certain new and useful Improvements in Steam-Engines, of which the following is a specification.

My invention relates to steam-engines, and has for its object the provision of an improved turbine-engine.

A further object of the invention is the provision in a turbine-engine of means for reversing the same.

A further object of the invention is the provision of means for stopping the idle rotation of the engine after the live steam has been cut off from the steam-chests.

A further object of the invention is the provision of means for causing the exhaust-steam from the high-pressure cylinders to aid in rotating the low-pressure cylinder.

Other objects of the invention will be set forth in the detailed description which now follows.

In the accompanying drawings, Figure 1 is a longitudinal vertical section of my improved turbine-engine. Fig. 2 is a transverse vertical section upon line *a a* of Fig. 3. Fig. 3 is a transverse vertical section upon line *b b* of Fig. 1.

Like numerals designate similar parts throughout the several views.

In my improved turbine-engine the numeral 20 designates a base, upon which is mounted a casing 21, composed of interior and exterior shells 22 and 23, respectively. This casing 21 is divided into compartments of different diameters, the several compartments being, respectively, designated by the numerals 24, 25, 26, and 27, the three former of which constitute the high-pressure steam-chests 28, 28', and 28'', and the latter the low-pressure steam-chest 28''. At each end the casing 21 is provided with bearings 29 for the reception of the main shaft 30 of the engine, and said bearings are made steam-tight by the provision of packing 31.

The high-pressure steam-chests 28, 28', and 28'' are formed between the shells 22 and 23, and a low-pressure steam-chest 28'' is formed in the compartment 27 of said shells.

Mounted upon the shaft 30 of the engine,

through the medium of radial arms 30' or otherwise, are the rotative cylinders 32, 33, 34, and 35, the peripheries of said cylinders fitting snugly against the interior surfaces of the compartments 24, 25, 26, and 27 of the shell 22, and said cylinders 32, 33, and 34 constituting the high-pressure cylinders of the improved engine, while the cylinder 35 constitutes the low-pressure cylinder of said engine.

Formed in the interior shell 22 and continued through the cylinders 32, 33, 34, and 35 are steam-ports 36, each port comprising a receiving portion 37, formed partially in the shell 22 and partially in one of the cylinders, and a discharge portion 37', formed wholly in the cylinders, as shown in Figs. 1 and 2. The receiving portions 37 of these ports extend through the shell 22 and partially through the walls of the cylinders, forming thereby pockets or cups 38 in the faces of the cylinders, against the bottoms of which the steam impinges to aid in rotating said cylinders. The discharge portions 37' of said ports extend from the interior of the cylinders to the receiving-passages of said ports and connect with said receiving-passages at a point slightly above the bottoms of the pockets or cups 38, said discharge-passages 37' being formed at an angle to the receiving-passages 37, though it is distinctly to be understood that I do not limit myself to the exact form of ports herein described and that the angles may be varied or other minor changes made without departure from the invention.

An exhaust-chamber 40 is provided between the shells 22 and 23, intermediate the high-pressure cylinder 34 and the low-pressure cylinder 35, said exhaust-chamber being provided with exhaust-ports 41, formed in the shell 22 and in the wall of the cylinder 34. These exhaust-ports are similar to the steam-ports 36, excepting that they are formed in an opposite direction to said ports 36, as illustrated in Fig. 3.

The exhaust-chamber 40 is divided into two compartments 42 and 43 by walls or partitions 44, said compartments being connected by a by-pass 45, provided with a valve 45' for a purpose hereinafter described.

Indicated at 46 is a live-steam pipe pro-

vided with a valve, (not shown,) said steam-pipe being in communication with the compartment 42 of the exhaust-chamber, said exhaust-chamber communicating with the 5 low-pressure steam-chest 28³ through the medium of an auxiliary discharge-pipe 47 and a live-steam pipe 48, said steam-pipe having branch pipes 49, 49', and 49², leading to the high-pressure steam-chests, and a drain or 10 waste pipe 50, which is provided with a valve. (Not shown.)

The steam-pipe 48 is provided with an injector-nozzle 51, situated between the branch pipe 49² and the auxiliary discharge-pipe 47, 15 the mouth or discharge-point of said nozzle projecting slightly beyond said pipe 47 for a purpose which will be hereinafter described.

The interior of the low-pressure cylinder 35 forms a low-pressure exhaust-chamber 53, 20 in communication with which is the exhaust-pipe 15.

The operation of the improved turbine-engine is as follows: When it is desired to rotate the cylinders forward or in the direction 25 indicated by the arrow in Fig. 2, live steam is admitted to the high-pressure steam-chests through the main steam-supply pipe 48 and the branch pipes 49, 49', and 49², and the steam entering the ports 36 and impinging at 30 boiler-pressure against the bottoms of the pockets 38 will cause the cylinder to rotate to the right, said steam being discharged through the passages 37' of said ports to the interior of the high-pressure cylinders. 35 While the cylinders are rotating in the above-described direction, the valves upon the steam-supply pipe 46 and the drain-pipe 50 are closed, while the valve 45' of the by-pass 40 is open to afford free communication between the compartments 42 and 43 of the exhaust-chamber. By providing the injector-nozzle 51 in the steam-supply pipe 48 a vacuum is formed in the exhaust-chamber 40, and as the steam is exhausted into said chamber 45 through the exhaust-ports 41 it is drawn into the low-pressure steam-chest 28³, where it aids in rotating the low-pressure cylinder 35 in the same manner that the high-pressure cylinders are rotated, and said steam passes from 50 the interior of said low-pressure cylinder through the exhaust-pipe 15 to any device where it may be utilized or to the stack. Any water of condensation collecting in the high-pressure cylinders will be discharged directly 55 into the interior of the low-pressure cylinder through ports 55, formed for that purpose in the wall of said low-pressure cylinder, as illustrated in Fig. 1. When it is desired to reverse the direction of rotation 60 of the cylinders, and thereby the shaft 30, the main steam-supply valve 100 and the valve 45' of the by-pass 45 are closed and the valve 101 upon the drain-pipe 50 is opened, after which steam is admitted by valve 46' 65 through the steam-supply pipe 46 at boiler-pressure to the compartment 42 of the exhaust-chamber, where it enters the exhaust-ports 41,

and as these ports are formed, as before stated, in an opposite direction to the steam-ports 36 it is evident that the cylinders will 70 be caused to rotate to the left or in the direction of the arrow shown in Fig. 3, the steam passing into the interior of the cylinders, as when the engine is rotating to the right, and exhausting through the ports 36 into the 75 steam-chests 28, 28', and 28², from whence it is discharged through the drain-pipe 50, steam-supply pipe 48, and branch pipes 49, 49' and 49².

In the operation of turbine-engines of the 80 class to which my invention relates it frequently happens that after the steam-supply to the cylinders has been shut off the inertia of the rapidly-rotating cylinders will cause them and the shaft to which they are connected to spin around idly or rotate rapidly for some time, and in the practical operation of machines of this class it has been a desideratum to provide means for overcoming this 85 objection.

In my construction live steam when introduced in the manner above described to the compartment 42 of the exhaust-chamber 40 will, as is obvious, forcibly retard and finally stop this idle rotation of the engine by acting 95 in a reverse direction to that of steam introduced in the usual way, and finally, if desired, may act to rotate the engine in a reverse direction.

As above stated, the exhaust-chamber 40 is 100 divided into two compartments by the walls or partitions 44, and these compartments are connected by a by-pass 45, having a valve 45', and when it is desired to "brake" the engine or finally to reverse it said valve 45' 105 is closed, the valve 100 in steam-pipe 48 is also closed, and the valve 101 in drain-pipe 50 is opened. Valve 46' in live-steam pipe 46 is now opened and steam at boiler-pressure is admitted to compartment 42, enters ports 41, 110 and owing to the reverse direction of said ports with relation to the ports 36 of all the other cylinders tends to rotate the shaft 30 in an opposite direction, the exhaust escaping into the interior of the exhaust-chamber 40, which 115 then acts as a reversing-cylinder, and, following the line of least resistance, flowing through the ports 41, pipes 47, and the ports of the high-pressure cylinders, their steam-chests, and piping connections to said drain-pipe 50. 120 Owing to the loss of its energy in tending to brake or reverse the engine the pressure of the steam escaping into the high-pressure cylinders from the reversing-cylinder is insufficient to cause any appreciable retarding 125 influence against the reversing force of the steam at boiler-pressure delivered to the chest 40 by pipe 46. It therefore follows that when the supply of steam to the high-pressure cylinders is "shut-off" and the steam 130 for "braking" and reversing is "turned on" free escape of the exhaust or low-pressure steam is provided for in the construction described. Any water of condensation collect-

ing in the reversing-cylinder will readily pass off, together with some exhaust-steam, through the ports 55, leading to the low-pressure cylinder 35, from which it passes by piping described to the drain-pipe 50.

The proportions of the braking and reversing cylinder may be varied as described; but as is obvious from what has just been stated said cylinder will act first to retard and finally 10 stop the motion of the engine in normal direction and then to reverse the direction of rotation thereof, if desired.

From the above description it will be seen that I have provided a reliable and positively-operated turbine-engine which may be readily reversed or stopped. It will be further seen that the exhaust-steam from the high-pressure compartments or cylinders may be utilized in this form of turbine-engine to aid 15 in rotating the low-pressure cylinder and that means are provided for taking such exhaust-steam from the exhaust-chamber to the low-pressure steam-chest.

While the compartments or cylinders of the 20 engine are shown of certain proportions, it is distinctly to be understood that said proportions may be varied as circumstances require and that the size of the exhaust-cylinder may be changed from that illustrated to one of 25 larger proportions, if desired. So, too, the forms of the ports for admitting and exhausting steam may vary from those shown, and the means for causing the motive fluid to be discharged from the cylinders and exhaust-chamber and the form and arrangement of 30 said cylinders may be changed without departure from the invention and any desired number of cylinders may be employed, the invention not being limited in this respect.

Having thus described my invention, what I claim is—

1. The combination, with a shell having inclined pockets and exhaust-ports, of means for supplying steam to the pockets; a retarding and reversing compartment carried by the shell, said compartment having pockets reversely inclined with relation to those of the shell, and also having exhaust-ports leading from said pockets; and means for supplying steam to said compartment.

2. A turbine-engine comprising a casing having a series of steam-chests of different sizes; means for supplying steam to said steam-chests; ports in the inner wall of said casing; a shell having a series of compartments of different sizes mounted for rotation within the casing; means carried by the shell for receiving the impact of steam from the ports in the steam-chests; and exhaust-ports 55 in the shell.

3. A turbine-engine comprising a casing having steam-chests; means for supplying live steam to said steam-chests; ports in the inner walls of the steam-chests; a shell having compartments provided with pockets communicating with said ports, said shell being mounted for rotation within the casing; exhaust-

ports leading from said pockets to the interior of the shell; a steam-chest for receiving exhaust-steam from said compartments, said steam-chest having ports; and a compartment of the shell having pockets communicating with the ports of the exhaust-steam chest, and also having exhaust-ports leading from said pockets.

4. A turbine-engine comprising a series of steam-chests for receiving steam; ports in the inner wall of each of said steam-chests; means for supplying steam to the steam-chests; a shell having compartments provided with 80 pockets communicating with the ports in the steam-chests, said compartments also having exhaust-ports leading from said pockets; means for supporting the shell within the casing; a speed retarding and reversing compartment carried by the shell and having pockets and exhaust-ports; a steam-chest having ports communicating with said pockets; and means for supplying steam to said steam-chest.

5. A turbine-engine comprising a casing 90 having steam-chests, each steam-chest being provided with ports; a shell mounted for rotation within the casing, and having a series of compartments provided with pockets communicating with the ports of the steam-chest, and with exhaust-ports leading from said pockets; a speed retarding and reversing compartment; a steam-chest having ports communicating with said compartment; means carried by said compartment for receiving the impact of steam from said steam-chest; and ports for exhausting the steam from said compartment.

6. A turbine-engine comprising a steam-chest, having ports; means for supplying steam to said steam-chest; a rotary shell having pockets communicating with the ports of the steam-chest; a speed retarding and reversing compartment carried by the shell; a steam-chest having ports; means carried by the speed retarding and reversing compartment for receiving the impact of steam from the ports of the steam-chest; exhaust-ports in said speed retarding and reversing compartment; and means for supplying steam to said speed retarding and reversing compartment.

7. A turbine-engine comprising a steam-chest having ports; means for supplying steam to said steam-chest; a rotary device having pockets communicating with the ports of the steam-chest, and also having exhaust-ports leading from said pockets; a speed retarding and reversing device having pockets and exhaust-ports; a steam-chest having ports communicating with the pockets of said speed retarding and reversing device; and means for supplying steam to said steam-chest.

8. A turbine-engine comprising a casing containing a steam-chest having a series of inclined ports; a shell mounted for rotation within said casing and having a series of inclined pockets communicating with the ports of the steam-chest, and also having a series of exhaust-ports leading from said pockets to

the interior of the shell; means for supplying steam to said steam-chest; and means for exhausting the steam from said shell.

9. A turbine-engine comprising a casing having a series of steam-chests, each steam-chest being perforated in its inner wall to form ports; a shell having compartments provided with pockets communicating with the ports of the steam-chests and with exhaust-ports leading from said pockets; a shaft journaled in the casing and to which said shell is secured; and means for exhausting the steam from said shell.

10. A turbine-engine comprising a casing; a series of steam-chests carried by the casing and each having discharge-ports; means for supplying steam individually to each of the steam-chests; a shell mounted for rotation within the casing and having a series of compartments provided with pockets communicating with the ports of the steam-chests, and with exhaust-ports leading from said pockets to the interior of the shell; an exhaust-compartment of the shell provided with pockets and exhaust-ports; and means for supplying steam exhausted from the other compartments to said exhaust-compartment.

11. A turbine-engine comprising a casing provided with steam-chests of different diameters, each steam-chest having a series of discharge-ports; a steam-pipe, branches from said steam-pipe leading to the steam-chests; and a shell mounted for rotation within the casing and having a series of compartments provided with pockets communicating with the discharge-ports of the steam-chest and with exhaust-ports leading from said pockets.

12. A turbine-engine comprising a steam-chest having a series of discharge-ports; a rotary shell having a series of pockets communicating with said discharge-ports, and also having exhaust-ports leading from said pockets; an auxiliary steam-chest adjacent to the other steam-chest and having a series of discharge-ports; a speed retarding and reversing compartment having a series of pockets communicating with said discharge-ports, and a series of exhaust-ports leading from said pockets; and means for supplying steam to said compartment to retard, and finally reverse, the motion of the engine.

13. A turbine-engine comprising a casing having steam-chests, the latter provided with discharge-ports; a shell mounted for rotation within the casing and having a series of pockets communicating with the discharge-ports of the steam-chests, said shell also having exhaust-ports leading from said pockets; a steam-supply pipe having a branch communicating with the steam-chests; and means for forcibly exhausting the steam from the shell.

14. A turbine-engine comprising a steam-chest having discharge-ports; a steam-supply pipe communicating with said steam-chest; a rotary shell having a series of pockets com-

municating with the ports of the steam-chests, and also having a series of exhaust-ports leading from said pockets; and means carried by the steam-supply pipe for exhausting steam from the shell.

15. A turbine-engine comprising a steam-chest having discharge-ports; a steam-supply pipe communicating with said steam-chest; a rotary shell having a series of pockets communicating with the ports of the steam-chest, and also having a series of exhaust-ports leading from said pockets; and an injector-nozzle carried by the steam-supply pipe for exhausting steam from said shell.

16. A turbine-engine comprising a casing having a series of steam-chests, each provided with discharge-ports; a shell having a series of compartments mounted for rotation within said casing, each compartment having a series of pockets, and also having a series of exhaust-ports leading from said pockets; a steam-supply pipe having branches communicating with the steam-chests; an injector-nozzle within the steam-supply pipe; and an exhaust-pipe leading from the casing.

17. A turbine-engine comprising a steam-chest, means for supplying steam to said steam-chest; inclined ports leading from the steam-chest; a rotary shell having inclined pockets communicating with the ports of the steam-chest, and also having exhaust-ports leading from said pockets; an auxiliary steam-chest having ports of reverse inclination to those of the main steam-chest; and an auxiliary compartment adjacent to the shell and having pockets of reverse inclination to those of the shell, and exhaust-ports leading from said pockets; and means for supplying steam to said auxiliary steam-chest.

18. A turbine-engine comprising a casing having a series of steam-chests, each provided with discharge-ports; means for supplying steam directly to each of said steam-chests; a shell having a series of compartments provided with pockets communicating with the ports of the steam-chests, and also provided with a series of exhaust-ports leading from said pockets; a shaft journaled in the casing and to which said shell is secured; a reversing-compartment carried by the shell; means for supplying steam to said reversing-compartment; and means for exhausting steam from the various compartments of said shell.

19. A turbine-engine comprising a casing having a series of steam-chests for the reception of steam under boiler-pressure, and also having a steam-chest for the reception of exhaust-steam; discharge-ports in each of said steam-chests; a shell mounted for rotation within the casing and having a series of compartments, each compartment having pockets communicating with the discharge-ports of the steam-chests; and means for supplying exhaust-steam from the shell to said exhaust-steam chest.

20. A turbine-engine comprising a high-

- pressure steam-chest having discharge-ports; an exhaust or low-pressure steam-chest having discharge-ports; an auxiliary steam-chest located between the exhaust and high-pressure steam-chests; a shell having a compartment provided with pockets in communication with the ports of the high-pressure steam-chest, and with a compartment having pockets in communication with the ports of the low-pressure steam-chest; a compartment intermediate the high-pressure and low-pressure compartments, and also having pockets communicating with the discharge-ports of the auxiliary steam-chest; means for supplying steam to the auxiliary steam-chest; means for supplying steam at boiler-pressure to the high-pressure steam-chest; and means for supplying exhaust-steam to the low-pressure steam-chest.
- 20 21. A turbine-engine comprising a casing having a series of high-pressure steam-chests and a low-pressure steam-chest; discharge-ports in each of said steam-chests; a shell having a series of high-pressure compartments provided with pockets communicating with the ports of the high-pressure steam-chests; a low-pressure compartment having pockets communicating with the ports of the low-pressure steam-chest; means for exhausting steam from the high and low pressure compartments; an auxiliary compartment carried by the shell, and located between one of the high-pressure compartments and the low-pressure compartment of said shell, said auxiliary compartment having pockets and discharge-ports communicating with said pockets; an auxiliary steam-chest having ports communicating with the pockets of the auxiliary compartment of the shell; means for supplying steam to said auxiliary steam-chests; means for supplying steam to the high-pressure steam-chest; and means for supplying exhaust-steam to the low-pressure steam-chest.
- 45 22. In a turbine-engine, the combination with means for rotating said engine in a forward direction; of a rotary shell having a series of pockets and a series of exhaust-ports leading from said pockets; a steam-chest having ports communicating with the pockets of said shell, said steam-chest being divided into compartments; and means for connecting the compartments of said steam-chest with each other.
- 55 23. In a turbine-engine, the combination, with means for rotating said engine in a forward direction, of a rotary shell having a series of pockets and a series of exhaust-ports leading from said pockets; a steam-chest having ports communicating with the pockets of said shell, said steam-chest being divided into compartments; a by-pass connecting the compartments of said steam-chest with each other; and a valve in said by-pass.
- 65 24. A turbine-engine comprising a casing having a series of high-pressure steam-chests, each provided with discharge-ports; a rotary shell having a series of compartments, each provided with pockets communicating with the discharge-ports of the steam-chest, and each having exhaust-ports leading from said pockets; means for supplying high-pressure steam to said steam-chest; a low-pressure steam-chest carried by the casing and having discharge-ports; means for supplying exhaust steam to said low-pressure steam-chest; a compartment carried by the shell and having pockets communicating with the discharge-ports of the low-pressure steam-chest, said compartment also having exhaust-ports communicating with said pockets; and an injector for forcing exhaust-steam into said low-pressure steam-chest.
- 25 25. A turbine-engine comprising a casing having a series of high-pressure steam-chests, each provided with discharge-ports, and a low-pressure steam-chest having discharge-ports; a shell having a series of pockets communicating with the discharge-ports of said steam-chests, also having a series of exhaust-ports leading from said pockets to the interior of the shell; a shaft mounted in the casing and to which the shell is connected; an auxiliary steam-chest carried by the casing; and a speed retarding and reversing compartment carried by the shell.
- 35 26. A turbine-engine comprising a casing having a series of high-pressure steam-chests provided with discharge-ports of one inclination; a high-pressure steam-chest having discharge-ports of reverse inclination to those of the other steam-chests; a shell having a series of compartments provided with pockets communicating with the discharge-ports of main steam-chest, and also having a compartment provided with pockets communicating with the discharge-ports of the auxiliary steam-chest; exhaust-ports leading from the pockets of each of said compartments; a high-pressure steam-supply pipe; an injector carried by said pipe; a low-pressure steam-chest having discharge-ports into which the exhaust-steam is forced by the injector; a compartment carried by the shell and having pockets communicating with the discharge-ports of the low-pressure steam-chest, and exhaust-ports leading from said pockets to the interior of said compartment.
- 40 27. A turbine-engine comprising a casing having a high-pressure steam-chest provided with discharge-ports; means for supplying steam to said high-pressure steam-chest; a rotary shell having pockets communicating with the discharge-ports of the high-pressure steam-chest, and also having exhaust-ports leading from said pockets; an auxiliary high-pressure steam-chest provided with discharge-ports; means for supplying steam to said auxiliary steam-chest; a compartment of the shell having pockets communicating with the discharge-ports of the auxiliary steam-chest, and also having exhaust-ports leading from

said pockets, the wall of said compartment being perforated to permit the escape of the water of condensation; means for dividing the auxiliary high-pressure steam-chest into 5 compartments; a by-pass connecting the compartments of said steam-chest; a valve in said by-pass; an injector for withdrawing exhaust-steam from said steam-chests; and

an exhaust-pipe leading from the casing of the engine.

In testimony whereof I affix my signature in presence of two witnesses.
